UNITED STATES PATENT OFFICE

EDWARD J. O'DONNELL, OF LOWELL, MASSACHUSETTS

DESIGN FOR A FONT OF TYPE

Application filed February 16, 1931. Serial No. 38,673. Term of patent 14 years.

To all whom it may concern:

Be it known that I, EDWARD J. O'DONNELL, a citizen of the United States, residing at Lowell, in the county of Middlesex and State of Massachusetts, have invented a new, original, and ornamental Design for Font of Type, of which the following is a specification, reference being had to the accompanying drawing, forming part thereof.

The drawing is a plan view of a font of type constituting my design.

I claim:

The ornamental design for a font of type, substantially as shown.

Signed at Lowell, in the county of Middlesex and State of Massachusetts, this twelfth day of February, 1931.

EDWARD J. O'DONNELL.
